UNITED STATES PATENT OFFICE

CHARLES E. CONSTABLE, OF CINCINNATI, OHIO, ASSIGNOR TO THE NATIONAL MARKING MACHINE COMPANY, OF CINCINNATI, OHIO, A CORPORATION OF OHIO

METHOD OF ASSORTING AND CLASSIFYING LAUNDRY ARTICLES

Original application filed June 28, 1928, Serial No. 288,979. Divided and this application filed June 4, 1929. Serial No. 368,333.

This application is a division of my co-pending application, Serial Number 288,979, filed June 28, 1928, to which reference is here made.

Laundry articles are usually received in a commercial laundry in individual family bundles which have to be broken and classified and assorted, and then conveyed to the proper washing mechanism, and at the same time the articles must be provided with suitable identification characters, whereby they may be collected and again formed into suitable bundles and delivered to the owners. 10 A large amount of work is involved in the proper assorting and classifying of the laundry articles, and considerable difficulty has been experienced in collecting the articles after they have been washed and again bundling them to avoid loss. 15 To simplify the assorting and classifying of the articles from the family bundles and to decrease the percentage of errors and loss, I have provided a new and improved method of assorting and classifying the articles 20 to be washed.

One of the objects of my invention is to provide an improved system or method of breaking the individual family bundles of laundry and preparing them for the wash room, and separating and classifying the articles with a minimum amount of labor, and at the same time with a high degree of accuracy to avoid mistakes. 25

A further object is to provide a mechanism whereby the above method may be more easily and quickly carried out, and whereby the chances of mistakes and errors are greatly reduced, and further whereby the articles of the bundles may be passed 30 progressively from one operator to another, the bundles being passed in a successive manner at regular intervals in such manner as to increase the speed of the work.

A further object of my invention is to 45 provide in connection with a mechanism of

the type above described means whereby the articles in one container will not become mixed with the articles in another container.

My invention consists in the relative arrangement of the various steps of the method, whereby the objects contemplated are attained, as hereinafter more fully set forth, pointed out in my claims, and illustrated in the accompanying drawings, in which:

Figure 1 is a plan view of one type of mechanism which may be used in carrying out my method.

Figure 2 is a side elevation of same.

Figure 3 is a vertical, longitudinal, sectional view.

Figure 4 is a perspective view of one of the identification pins used in connection with my method.

My improved method can best be explained by first describing one form of mechanism for carrying out the method. Said mechanism is preferably mechanically operated, although it will readily be seen that hand operated mechanism may be substituted.

The mechanism illustrated comprises a frame 10 supported by legs 11. The ends of the frame are provided with rollers 12 and 13 designed to support and carry a continuous belt 14. The upper run of said belt is designed to travel on a slatted platform 15. The frame 10 has upwardly extending side members 16 and 17, which extend substantially the entire length of the frame. The member 16 terminates inside of the end of the frame a slight distance, while the member 17 terminates a greater distance from the same end of the frame. A short side member 18 is provided so that a notch or opening is formed between the members 17 and 18.

The belt 14 is provided with a series of transversely arranged upright partitions 26, which are of a height substantially equal to the height of the side members 16 and 17.

and of a length slightly less than the distance between said side members, as clearly illustrated in Fig. 1.

The belt is designed to travel in an anti-clockwise direction, as illustrated in Figures 2 and 3. The partitions 26 are preferably mounted equidistantly. The partitions of the upper run are designed to travel between the side members to form compartments 28 for receiving the laundry articles, each compartment being designed to receive and carry all articles in an individual family bundle.

A chute 29 is provided at the receiving end of the belt having its lower edge terminating at a point immediately above the first one of the partitions 26, as illustrated in Figure 3, for receiving the family bundles and for delivering the same to the belt.

20 A platform 30 is provided near the receiving end of the belt on which a number of family bundles may be placed.

Adjacent to the rear end of the side member 17, and outside of the frame 10, is a 25 pair of net or bag holders 31, and spaced rearwardly from the net holders 31 is another net holder 32. The net holder 32 and the rear net holder 31 are spaced apart such a distance as to permit an operator to 30 stand between them. Said spacing forms what I shall term station D.

The opposite end of the frame 10 is provided with a pair of net holders 33, spaced apart to receive an operator between them, 35 said spacing forming station E. Each of said stations is provided with an operator. Operators are also located at stations A, B and C. Station A is located near the receiving end of the belt, while stations B and 40 C are located substantially midway between the upright partitions adjacent to station A.

The roller 12 is provided with an extended shaft 34, having a belt 35 driven by a motor 36. The electric conductors 37 of the motor 45 include a switch 38, whereby the motor may be started and stopped, and in turn the movements of the belt controlled.

Frame members 39 are preferably anchored to the sides of the frame through 50 which partitions 26 travel. Said frames are spaced apart a distance equal to the spacing of the partitions 26. Said frames provide means for determining the stopping positions of the partitions, as well as supporting 55 the curtains 40 which assist in keeping articles of the adjacent family bundles separated.

The switch 38 is located near the delivery end of the belt where it may be actuated by 60 either of the operators in stations D and E.

In carrying out the operation of my improved method, an operator is placed in each of the stations A, B, D and E, and one or more individual family bundles delivered to 65 the platform 30, one of the bundles is then

grasped by the operator in station A, and is then weighed and the weight of the bundle is recorded together with the number of the identification device, which is preferably a pin 41, such as illustrated in Figure 4. A pin tray 42 is then placed on the belt 14 in the first compartment at the receiving end. This pin tray is adapted to contain a number of the pins 41, all of which bear the same identification number or mark. The bag is then broken and the contents emptied into the chute 29 and delivered thereby to the belt. The articles are designated by the numeral 43. The empty bag 44 is then placed on the belt 14 adjacent to the second partition 26.

The switch 38 is then operated and the belt 14 advanced a distance equal to the spacing of the cleats 26, after which the motor is again stopped. The articles 43 will then rest in the second compartment in the receiving end of the conveyor in front of the operator in station B.

A second bundle is at this time introduced to the chute 29 as before described. At the same time the operator in station B separates the white articles from the colored ones, placing the white articles in a pile 45 adjacent to the forward partition of said compartment, and the colored articles in a pile 46 adjacent to the rear partition of said compartment, as indicated in Figure 1, and at the same time spread out the articles for easy access by the operators.

At this time the belt is again advanced 100 one step in the manner above described, bringing the piles 45 and 46 in front of station C. The operator at station C classifies all colored articles for washing, places them in a pile 47 and marks all fugitives with separate pins from the tray 42 and then places them in a pile 49, and the hand wash articles in a pile 50.

The conveyor is again advanced one step, carrying the piles 47 in front of the operator at station E and the piles 49 and 50 in front of the operator at station D.

The operator in station E then places nets on the holders 33, after which the articles in the piles 47 are scraped off into the nets in the holders 33. Said nets are then pinned with identification pins taken from the tray 42. The operator in station D at the same time places the colored articles in a net in the holder 32, and the fugitives and hand wash articles in nets in the holders 31, and pins the nets with identification pins from the tray 42, after which the nets are ready for distribution in the proper washing machines.

By this arrangement it will be seen that the belt is advanced a step at a time and allowed to remain stationary during the time the operators in all of the stations perform the various operations, said opera-

tions taking place simultaneously. By this method team work is established among the operators, and the operator in one station must perform her work in the same length 5 of time as required for operators in other stations, thereby preventing delays and confusion that might otherwise be caused by one operator not keeping up with her work, and thus the work is rapidly and accurately 10 performed.

It will readily be seen that articles from a given bundle are placed in a compartment and retained in said compartment as it is advanced through all of its operations. 15 The assorted piles are placed in suitable nets, and all of the nets containing articles from a given compartment are pinned with pins from a given tray, so the nets may be collected after the washing has been performed and the articles again placed in suitable bundles on which is placed the original ticket corresponding to the particular identification number or mark.

It should be borne in mind that each time 25 a new bundle is placed in the chute a new pin tray is also placed on the belt 14 in that particular compartment. The pins of one tray have different identification numbers from those of the other trays.

30 Thus means is provided whereby each individual washing or family bundle may be broken and classified into a number of piles, each of which is provided with a given identification number.

35 The identification pins in the trays may be of any one of a number of such devices now in common use, or other identification means may be substituted for the pins, inasmuch as the particular apparatus described herein forms no part of my present 40 invention other than to show a practical means for carrying out my improved method. It will readily be seen that even the transverse partitions may be dispensed 45 with, or even the belt itself. However, the invention is best carried out by means of some moveable carrier or platform.

My improved method consists broadly in providing a number of classifying stations 50 and an operator for each station, then delivering to the first operator of the series a family bundle, breaking the bundle, weighing the same and recording the weight of the bundle with the name of the owner of 55 the bundle, together with an identification device; and so locating the stations and operators that the broken bundle of mixed laundry articles may be advanced progressively past all of the stations, the first bundle 60 being followed successively by other bundles, all of the bundles being advanced simultaneously and allowed to rest a short period of time in front of the respective operators, at 65 which time the operators perform assigned assorting and classifying operations; and ap-

ply to the assorted piles identification devices carrying the number or mark identifying the owner; pin all fugitives; hand wash articles, etc. with similar identification marks that are applied to the piles; and finally places 70 the remaining classified articles into individual nets and applying to each net an identification device.

I claim as my invention:

1. The method of assorting laundry articles which consists in first establishing a series of operators' stations, then advancing past said stations a series of compartments designed to contain laundry articles, and stopping each compartment temporarily 75 adjacent to each station, and then during the time that each compartment is standing adjacent to each station performing by the operator an assorting portion of the complete assorting operation so that each operator 80 may perform the same portion of the assorting operation upon each set of laundry articles in each compartment.

2. The method of assorting laundry articles which consists in first establishing 90 a series of operators' stations then advancing past said stations a series of compartments designed to contain laundry articles, and stopping each compartment temporarily 95 adjacent to each station, and then during the time that each compartment is standing adjacent to each station performing by the operator an assorting portion of the complete assorting operation so that each operator 100 may perform the same portion of the assorting operation upon each set of laundry articles in each compartment.

3. The method of assorting laundry 110 articles, which consists in establishing a series of operators' stations then advancing past said stations a series of compartments designed to contain laundry articles, then delivering bundles of mixed laundry articles 115 to the first station, then breaking the bundle, then advancing the articles of said bundle to a second station during the time a second bundle is being delivered to the first station, performing an assorting operation on the 120 articles of the first bundle, advancing the bundles simultaneously to other stations and reassorting and classifying the articles for washing, and applying to each classified lot an identification mark, and finally placing 125 the assorted articles into separate nets and applying identification marks to each of the nets.

4. The method of assorting laundry articles which consists in establishing a series of 130

operators' stations, then advancing past said stations a series of compartments designed to contain laundry articles, then delivering bundles of mixed laundry articles to the first station, then breaking the bundle, then advancing the articles of said bundle to a second station during the time a second bundle is being delivered to the first station, performing an assorting operation on the articles of the first bundle, advancing the bundles simultaneously to other stations and reassorting and classifying the articles for washing.
